TEMPORARY BOLTING DEVICE

Nathan Kasdan, Plainfield, Conn.

Application June 11, 1943, Serial No. 490,443

4 Claims.

(Cl. 85—33)

This invention relates to an improved temporary bolting device.

The prime object of the present invention pertains to the provision of an improved bolting device operative for effectively drawing together and temporarily bolting metal parts such as steel sheets and plates preparatory to permanently uniting such metal parts as by riveting.

In riveting together steel plates in building various metal structures, it is the practice to draw together and secure the metal plates or sheets at a plurality of points by means of bolting-up devices inserted through the registering holes in said plates that later serve for the riveting operation. These devices temporarily hold the plates together and are later replaced by rivets. Various devices have been used for this temporary bolting operation. These have ranged from large power operated machines to small hand or finger operated so-called caps, depending upon the character of work to be performed. Ordinary bolts and nuts have also been used, but the latter requiring as they do very inconvenient manipulation from both sides of the plates, have proved unsatisfactory. Power operated machines are cumbersome and unwieldy for general work; and the smaller units are only adaptable for very thin sheets and, therefore, have a limited application.

The prime object of my present invention relates to the provision of a temporary bolting device of the small unit and manually operated type which is usable with ordinary bolts but which may be completely handled or operated from one side of the plates or sheets to be secured. A corollary object of the invention relates to the provision of such a bolting device which constructionally meets the major requirements met with in practice, such as serviceability with plates or metal parts having a wide range of thicknesses, the ability to be used in quantity for a given piece of work, simplicity of construction and certainty of functioning, and the ability of being applied to and removed from the work with great rapidity, in addition to being capable of being used with ordinary bolts and manipulated from one side of the assembled work.

To the accomplishment of the foregoing and such other objects as may hereinafter appear, my invention is directed to the provision of a temporary bolting device such as is sought to be defined in the appended claims and described in the following specification taken together with the annexed drawing, in which:

Fig. 1 is a vertical elevational view with parts

shown in section of one form of the temporary bolting device of the present invention, depicting the manner of its use and showing the same in the initial position when applied to the work;

Fig. 2 is a similar view of the same and showing the same in a final position when applied to the work;

Fig. 3 is a perspective view of the gripper member of the device;

Fig. 4 is a perspective view on a reduced scale of the bolting device of Figs. 1 and 2; and

Fig. 5 is a view corresponding to Fig. 2, but showing a modified structure of the device.

Referring now more in detail to the drawing and having reference first to Figs. 1 to 4 thereof, the temporary bolting device of the invention comprises a unit generally designated as A, intended and adapted to be used with bolts such as B for drawing together and temporarily securing in drawn-together condition a plurality of metal parts such as the metal plates or sheets generally designated as C at the registering riveting openings 10 of these plates. A plurality of bolts such as B are loosely inserted from the back 20 of the plates through these registering openings and a plurality of bolting devices A are applied to the work by being placed in the position shown in Fig. 1 of the drawing and are then wholly manipulated from the front side of the plates to draw up the bolts B and thereby draw together the plates C, securing these plates in the bolted-up condition as shown in Fig. 2 of the drawing.

The bolting device A comprises an elongated hollow casing generally designated as 12 for mounting and housing the operating parts, an operating member generally designated as 14 rotatably mounted at the top of the casing 12 and a gripping member generally designated as 16 in said casing suspendedly mounted from the operating member. The casing 12, besides defining the means for supporting and housing the operating member 14 and the gripping member 16, forms a hand hold for the device, the outer wall of the same being knurled as at 18 for this purpose. The operating member 14 and the gripping member 16 as well as the casing 12 are so related and so constructed that upon rotation of the operating member in one direction, the gripping member is caused to engage the thread 20 of the bolt B and to draw the bolt to draw up and secure the plates C together, and upon rotation of the operating member 14 in the opposite direction, the gripping member 16 is caused to disengage and release the bolt B.

The hollow casing 12 is preferably made cylindrical in form and is shaped to provide a top internally threaded end 22, a bottom preferably flanged, surface engaging end 24, an external finger-hold wall 26, and an internal camming wall 28, the camming part of which consists of an inclined shoulder 30 formed between the main body of the casing and the lower diameter enlarged part of the casing, as clearly shown in Figs. 1 and 2.

The operating member 14 comprises a threaded stem 32 which mates with the casing threaded end 22 as clearly shown in Figs. 1 and 2 of the drawing, and a fingerpiece which may be in the form of a knurled wheel 34 secured to the top of the stem 32, rotation of the fingerpiece 34 functioning to rotate the stem and thereby threadedly move the same longitudinally of the casing between the descended and elevated positions shown respectively in Figs. 1 and 2 of the drawing.

The gripping member 16 is suspendedly mounted from the bottom end of the operating stem 32 so that the latter may be rotated relatively to the former, and the said gripping member comprises two laterally movable jaws 36 and 38 adapted to engage the threads 20 of the bolt B and provided with the lateral extensions 40 and 42 adapted to be engaged and disengaged by the camming wall 30 of the casing when and as the said gripping member is moved longitudinally of the casing, engagement causing the jaws to contract laterally and disengagement permitting the jaws to expand laterally. The jaws 36 and 38 are internally threaded, and when made of a stamping, may be bodily threaded as clearly shown in Figs. 1, 2 and 3 of the drawing, for effecting efficient engagement with the threads 20 of the bolt B over a substantial portion of the length of the bolt. The gripping member 16 is suspendedly mounted in the operating member 32 to permit free rotation of the latter relatively to the former, by loosely riveting the circular top portion 44 of the gripping member 16 to the stem 32 by means of the rivet element 46. In assembling the operating member and the gripping member to the casing, this riveting step may be used as the last step of the assembling operation.

It is desired to effect an initial gradual engagement and drawing up of the bolt B and an operation of the parts so that when finally bolted up, the plates are drawn together and secured tightly and effectively. To this end, the parts are constructed to permit a substantial longitudinal movement of the gripping member as between the position of Fig. 1 and the position of Fig. 2, the initial engagement with the threads of the bolt B being the loose receptive engagement shown in Fig. 1 and the final engagement being the thread locking one shown in Fig. 2. In the first position the lower ends of the jaws 36 and 38 may protrude a substantial distance from the lower opening 48 of the casing 12, and in the second position lateral extensions 40 and 42 of the gripping member, after having passed the camming shoulder 30, are tightly in engagement with the reduced wall of the casing as best shown in Fig. 2 of the drawing.

In Fig. 5 of the drawing, I show a somewhat modified structure of the device in which the gripping member is mounted on and assembled with the operating member by means of a separate screw instead of by being riveted thereto, so that if desired, the parts may be more readily disassembled and may be assembled without a riveting operation. The parts of the device shown

in Fig. 5 are otherwise the same and are designated by similar but primed reference characters. The mounting of the gripping member 16' to the stem 32' of the operating member 14' is by means of a screw 48, the head 50 of which engages the circular top 44' of the gripping member and the shank of which is centrally received by the stem 32', the threaded terminus 52 of the screw having the lock nut 54 applied thereto loosely enough to permit rotation of the operating member 14' relative to the gripping member 16'.

The operation and use of the temporary bolting device described will be apparent. The device is a small unit as shown in Fig. 4 of the drawing. With the parts in position as shown in Fig. 1, the device is placed over the threaded shank of the bolt B, inserted loosely through the plates C. The fingerpiece 34 is then rotated to move the operating member 14 to the position shown in Fig. 2 of the drawing, while the casing 12 is held by the fingers of the user. The casing 12 is thereby moved into engagement with the top one of the plates C, while the gripping member 16 moves up longitudinally within the casing. The resilient gripping jaws 36 and 38 of the gripping member at first loosely engage the threads of the bolt B and gradually move into gripping engagement, this gripping being increasingly firmly effected as the lateral projections 40 and 42 of the gripping jaws move over the camming shoulder 30 of the casing. At this time the plates have been drawn together, the bottom end 24 of the casing being firmly seated on the top one of the plates C. The final incremental turn of the operating member causes the parts to finally assume the position shown in Fig. 2 with the plates in firmly bolted condition. By reverse rotation of the operating member, the ungrinding and releasing of the bolt may be quickly effected. By means of this simple construction, all of the advantages set forth hereinabove are obtained.

While I have shown the device in its preferred forms, changes may be made therein without departing from the spirit of the invention defined in the following claims.

I claim:

1. A temporary bolting device for temporarily bolting together metal parts through the medium of a bolt projecting therethrough, comprising a hollow casing, an operating member threadedly mounted at the top end of the casing, the casing being open at its bottom end to receive the bolt, a gripping member in said casing suspendedly mounted from the operating member the latter being rotatable relatively to the former, the gripping member comprising laterally contractable and expandible gripper jaws adapted to engage and disengage the threads of said bolt, means in said casing and on said gripper jaws operative when the gripper member is moved longitudinally in the casing for causing the bolt engaging and disengaging action of the gripper jaws, the said casing forming a finger hold and the bottom of said casing being adapted to engage the surface of the metal part to be bolted, rotation of said operating member in its threaded mounting being effective for moving the gripper member longitudinally in said casing and thereby causing gripping and drawing of the bolt and ungrinding and releasing of the bolt.

2. A temporary bolting device for temporarily bolting together metal parts through the medium of a bolt projecting therethrough, comprising a hollow elongated casing, a headed operating member threadedly mounted at the top end of the

casing, the casing being open at its bottom end to receive the bolt, a gripping member in said casing suspendedly mounted from the operating member the latter being rotatable relatively to the former, the gripping member comprising laterally contractable and expandible gripper jaws threaded to engage and disengage the threads of said bolt, said gripper jaws being movable through the open end of the casing, means in said casing and on said gripper jaws operative when the gripper member is moved longitudinally in the casing for causing the bolt engaging and disengaging action of the gripper jaws, the said casing forming a finger hold and the bottom of said casing being adapted to engage the surface of the metal part to be bolted, rotation of said operating member in its threaded mounting being effective for moving the gripper member longitudinally in said casing and thereby causing gripping and drawing of the bolt and ungripping and releasing of the bolt.

3. A temporary bolting device for temporarily bolting together metal parts through the medium of a bolt projecting therethrough, comprising an elongated hollow casing having an internal camming wall, an external fingerhold wall, a top internally threaded end, and a bottom surface engaging end, the said bottom end being adapted to engage the surface of a metal part to be bolted, an operating member comprising a threaded stem mating with said casing threaded end and a fingerpiece at the top of the stem for rotating the stem, and a gripping member in said casing suspendedly mounted from the stem, said stem being rotatable relative to said member, the gripping member comprising laterally movable jaws adapted to engage the threads of said bolt and provided with lateral extensions adapted to be engaged and disengaged by the camming wall of the casing when said member is moved longitudinally of the casing, engagement causing the jaws

tudinally of the casing, engagement causing the jaws to contract laterally and disengagement permitting the jaws to expand laterally, rotation of said fingerpiece being effective for rotating the stem on the casing and thereby moving the gripping member longitudinally in the casing for causing the gripping and drawing of the bolt and the ungripping and releasing of the bolt.

4. A temporary bolting device for temporarily bolting together metal parts through the medium of a bolt projecting therethrough, comprising an elongated hollow casing having an internal camming wall, an external fingerhold wall, a top internally threaded end, and an open bottom surface engaging end, the said open bottom end being adapted to engage the surface of a metal part to be bolted, an operating member comprising a threaded stem mating with said casing threaded end and a fingerpiece at the top of the stem for rotating the stem, and a gripping member in said casing suspendedly mounted at the bottom of the stem, said stem being rotatable relative to said member, the gripping member comprising laterally movable jaws threaded internally to engage the threads of said bolt, said jaws being provided with lateral extensions adapted to be engaged and disengaged by the camming wall of the casing when said member is moved longitudinally of the casing, engagement causing the jaws to contract laterally and disengagement permitting the jaws to expand laterally, said gripper jaws being movable through the open end of the casing, rotation of said finger-piece being effective for rotating the stem on the casing and thereby moving the gripping member longitudinally in the casing for causing the gripping and drawing of the bolt and the ungripping and releasing of the bolt.

NATHAN KASDAN.
